UNITED STATES PATENT OFFICE.

ELI FRIEDRICH, OF BROOKLYN, NEW YORK.

DESIGN FOR RUG FRINGE.

Application filed April 5, 1929. Serial No. 30,771. Term of patent $3\frac{1}{2}$ years.

To all whom it may concern:

Be it known that I, ELI FRIEDRICH, a citizen of the United States of America, residing in Brooklyn, county of Kings, State of New York, whose post-office address is No. 8002 21st Avenue, Brooklyn, county of Kings, State of New York, have invented a new, original, and ornamental Design for Rug Fringe, of which the following is a specification, reference being had to the accompanying drawing, forming part thereof.

The figure is a plan view of rug fringe showing my new design.

I claim:

The ornamental design for rug fringe substantially as shown.

ELI FRIEDRICH.
